UNITED STATES PATENT OFFICE.

ISAAC B. KELLER, OF STEELTON, PENNSYLVANIA.

DESIGN FOR SHIRT SLEEVES AND YOKE.

SPECIFICATION forming part of Design No. 33,566, dated November 13, 1900.

Application filed October 4, 1900. Serial No. 32,057. Term of patent 7 years.

To all whom it may concern:

Be it known that I, ISAAC B. KELLER, a citizen of the United States, residing at Steelton, in the county of Dauphin and State of Pennsylvania, have invented and produced a new and original Design for Shirt Sleeves and Yoke; and I do hereby declare the following to be a full, clear, and exact description of the same, reference being had to the accompanying drawings, forming a part thereof.

The design consists in the outline configuration of the shirt sleeves and yoke, the yoke portion being intermediate with the sleeve portions.

15 The essential feature of the design consists in the sleeve portions A B, having at their ends straight edges *a*, which are inclined from a perpendicular in a direction inwardly.

20 The upper edges *b* of the sleeve portions A B are perfectly straight on a horizontal line, while the lower edges *c* are on an incline, the greater width of the sleeve portions being at their inner ends and gradually de-

creasing in width in a direction toward their outer ends.

25 The inner ends of the sleeve portions A B at their edges have a double curve *d e* and *f g*, the curved edges *e* joining each other to form the yoke portion C, which yoke portion is located intermediate with the sleeve portions.

30 The yoke portion C increases in width as it joins the sleeve portions A B, and the lower edge of the yoke portion is formed with an arch, as shown at *h*.

35 Having now fully described my invention, what I claim as new, and desire to secure by Letters Patent, is—

30 The design for shirt sleeves and yoke as herein shown and described.

40 In testimony whereof I affix my signature in presence of two witnesses.

ISAAC B. KELLER.
